UNITED STATES PATENT OFFICE.

ERNEST W. LILJEGRAN, OF MEDFORD, OREGON.

EXERCISING DEVICE.

1,250,905.

Specification of Letters Patent. Patented Dec. 18, 1917.

Application filed November 11, 1916. Serial No. 130,872.

To all whom it may concern:

Be it known that I, ERNEST W. LILJEGRAN, a citizen of the United States, residing at Medford, in the county of Jackson and 5 State of Oregon, have invented new and useful Improvements in Exercising Devices, of which the following is a specification.

This invention relates to an exercising device.

10 In carrying out the invention it is my purpose to construct a yieldable platform and to arrange thereon a figure which is adapted to be contacted by the gloved hands of the person exercising and which has associated therewith a recording apparatus whereby the number of blows delivered upon the said figure and the force of the blows will be indicated.

It is a further object of the invention to 20 produce an exercising apparatus including a yieldable platform having a figure hingedly secured thereon, said figure being constructed of spring material to insure the flexibility thereof and being provided with 25 compressible parts in the nature of inflated members and such parts providing the objects to be contacted by force of blows delivered thereon by the person exercising, the inflated parts having tubular connections 30 with the registering and recording apparatus, the said recording apparatus also including a motor in the nature of a clock which is adapted to sound an alarm at determined intervals to denote the intervals 35 between rounds, means being provided between the hinged connection of the figure upon the platform for normally sustaining the figure in an upright position, said means being operative by the impact of 40 force, such as a blow of greater force than that usually delivered upon the figure to unlatch the said hinge to permit of the figure being swung by the impact of such a blow upon the platform.

45 It is also my purpose to produce an exercising apparatus comprising a yieldable platform which is adapted to bring into play muscles designed to steady the legs to insure confidence in the equilibrium and 50 poise of the person exercising to provide upon the platform a yieldable life-size figure or dummy which is so constructed as to simulate the motions of an animated body when influenced by the yieldability of the platform or by the impact of the force of the 55 blows thereon delivered by the person exer-

cising and also to provide means whereby the number and force of blows delivered to the said figure will be indicated and recorded.

With the above and other objects in view the improvement resides in the construction, combination and arrangement of parts set forth in the following specification and falling within the scope of the appended 60 claims.

In the drawings:

Figure 1 is a perspective view of an exercising device constructed in accordance with the present invention,

Fig. 2 is an approximately central vertical longitudinal section through the same, the dummy or figure being in elevation,

Fig. 3 is a greatly enlarged vertical longitudinal sectional view through the dummy 70 or figure,

Fig. 4 is a transverse sectional view through the same illustrating the manner in which the figure is supported upon the hinged plate, and

Figs. 5 to 7 illustrate details.

In carrying out my improvement I provide a substantially rectangular frame 1 which is designed to represent a roped arena, and adjacent to or at the corners of the frame I secure helical springs 2 which support a platform 3 upon the frame. Upon the bottom of the frame and at the corners of the platform I arrange buffer members 4-4 which are designed to contact with the platform to limit the downward movement thereof, when the said platform is subjected to weight or vibration incident to the movement of the person exercising thereon. The springs 2 are preferably provided with adjustable means, and also means, such as resilient plates 4', are arranged at the sides of the frame to limit the lateral movement of the platform, and similar bowed spring plates 4" may be provided at the ends of the 90 frame to limit the longitudinal movement of the platform.

Pivots secured to the platform 3, preferably at the center thereof but at a suitable distance from either of the ends of the said platform is a plate 5. Pivots secured transverse of the opening 6 in the platform is a trigger 7, and this trigger normally engages the plate at the end opposite the pivot or hinge thereof to sustain the said plate 105 flush with and flat upon the platform.

Arranged below the platform and sup-

ported in any desired manner is a cylinder 8 within which is arranged a piston head 9 having a piston rod 10, the said rod projecting through the closed upper end of the cylinder and disposed in the path of contact with the trigger 7, whereby to actuate the trigger and to release the plate 5, when the piston 9 is moved upwardly or outwardly of the cylinder, in a manner and for a purpose 10 which will presently be described. Arranged upon the piston rod 10 between the outer or upper closed end of the cylinder and the piston head 9 is a spring 11 which normally forces the head 9 in one direction 15 in the cylinder and the rod 10 away from contacting relation with the trigger 7.

Upon the plate 4 I arrange a dummy or figure 12, the same being shaped and proportioned to simulate the figure of a male 20 human being. This figure is preferably constructed from coiled wire so arranged as to assure the upright position of the figure but also devised to permit of the yielding of the said figure when the same is subjected to the 25 force of contact from the fists of the person exercising. The spring body of the figure 12 is provided with a suitable covering of some soft textile material. The figure 12 is secured to the plate 5 preferably through the 30 medium of a substantially U-shaped metal member or bolt 13 which has its arms passed through the spiral legs of the dummy and its connecting member arranged at the crotch between the legs of the dummy. The arms 35 14 of the U-shaped spring may be bolted or otherwise secured to the plate 5.

The figure or dummy 12, at the face and chest portions thereof has arranged thereon compressible members 15 and 16 respectively, 40 each of the said members being in the nature of inflatable bags but, of course, shaped to conform to the portions of the anatomy of a human being. A tube or hose 17 connects the inflated bags 15 and 16, and a similar tube or hose 18 is connected with the inflatable bag 16 and is directed through one of the spiral legs of the figure through suitable openings in both the plate 10 and the platform 3, the said tube having connected 50 thereto a branch 19 which communicates with the lower or outer closed end of the cylinder 8. The tube 18 is also connected with an air pump 20 and is provided adjacent to the said air pump with a branch communicating with an air gage 21. The conducting tube 18 is provided with an additional branch 22 which communicates with one end of a cylinder 23, the said cylinder having arranged therein a spring pressed 55 piston 24 provided with a piston rod 25 which passes through a packing box in the second end of the cylinder and which has its end pivotally connected, as at 26, to an arm 27 which is provided with a marking element 28, the said marking element being arranged

over a recording sheet 29. The arm 27 may if desired be pivoted, as at 30, so that the pivotal connection between the said arm and the piston rod 25 is loose to insure the free working of the arm. The recording sheet 70 75 may be of any desired or preferred design and is preferably secured to a support 31, and also connected with the said support is a motor in the nature of a clock 31', the said clock having its hand so arranged as to contact with a spring pressed trigger upon a spring actuated alarm 32 at desired intervals, and these intervals are so spaced as to indicate the time expiring between the rounds of boxing by the person exercising 80 and the dummy.

The conducting tube 18 adjacent to the air gage 21 is provided with a cock or valve 33 and the branch pipes of the said conducting pipes leading to the cylinders 8 85 and 23 are likewise provided with cocks or valves 34 and 35 respectively, and the said cocks 34 and 35 are turned off and the cock 33 is turned on when the pump is actuated to inflate the compressible bags 15 90 and 16 on the figure. When the said bags are inflated to the desired extent the cock 33 is turned off and the cocks 34 and 35 are turned on. The air between the inflated bags and the cylinders 8 and 23 are not sufficient to influence the pistons in the said cylinders, and the spring 11 in the cylinder 8 is of a materially greater strength than the spring within the cylinder 23, so that the piston 24 is easily influenced by air being forced therein upon the compression of either of the bags 15 and 16, but the spring within the said cylinder 23 will have a tendency to return the air to the said bags 15 and 16 after the piston in the said cylinder 105 23 has been actuated to operate the marking element 28 upon the arm 27. The piston in the cylinder 8 is, it will thus be noted, arranged to be operated only when a great amount of air has been forced therein, such 110 as would be caused by a great impact of force delivered upon either of the inflated bags 15 and 16, and when this piston is operated the piston rod will contact with the trigger 7 so that the force of the blow 115 will cause the plate 5 to swing upon its pivot or hinge and cause the figure to be swung against the platform.

To return the figure to its upright position, I secure to the plate 5 a flexible element 36 which is trained around pulley or sheave wheels 37 and which is connected to a pivoted lever 38, as clearly illustrated by the drawings.

Having thus described the invention, what 125 I claim is:

1. In an exercising device for boxers, a yieldable platform, a yieldable contact figure supported upon the platform, compressible elements upon the figure, recording 130

- means, and means, actuated by contact with the compressible elements for actuating the recording device.
2. In an exercising device for boxers, a spring supported platform, a yieldable figure upon the platform, inflatable elements upon the figure, a cylinder having a piston therein, tubes connected with the inflatable elements and with the cylinder, and an indicating member connected with the rod of the piston and disposed to be actuated when air is forced by the compression of the said inflatable elements and the action of such air upon the piston.
- 15 3. In an exercising device for boxers, a platform, a yieldable figure upon the platform, inflatable bags upon the figure, a cylinder, a piston in the cylinder and having a rod extending therethrough, a marking element connected with the rod, a record sheet for the marking element against which the marking element bears, tube connections between the inflatable bags and the cylinder, whereby to actuate the piston in the cylinder when one of the bags is compressed, and means for injecting a fluid to within the bags.
- 20 4. In an exercising device for boxers, a figure constructed of coiled springs, inflatable bags upon the figure, a cylinder, a spring pressed piston within the cylinder and having a rod projecting through the cylinder, an arm connected with the rod, a marking element upon the arm, a record sheet against which the marking element contacts, tube connections between the inflatable bags and the cylinder, a pump connected with one of the tubes, a gage for the pump, and cocks upon the tube between the gage and cylinder.
- 25 5. In an exercising device for boxers, a hinged plate, a yieldable contact figure upon the plate, a trigger upon the plate, a cylinder having a spring pressed piston therein having a piston rod disposed normally out of contact with the trigger, a second cylinder having a piston therein and having its piston rod projecting through the cylinder, a comparatively light spring influencing the piston, a pivoted arm loosely connected with the said piston rod, a marking element upon the arm, a record sheet against which the marking element bears, a tube connecting the inflatable bags, a tube from one of the inflatable bags connecting both of the pistons, means for injecting a fluid to within the inflatable bags, a cable connected with the hinged plate, and an operating lever for the cable, all as and for the purpose set forth.
- 30 6. In an exercising device, a spring supported platform, means for adjusting the tension of the springs, and a yieldable figure supported upon the platform.
- 65 7. In an exercising device, a frame, a yieldable platform arranged within the frame, means comprising resilient elements for limiting the lateral and longitudinal movement of the platform, and a yieldable figure supported upon the platform.
- 70 8. In an exercising device for boxers, a yieldable platform, a figure supported upon the platform and having its body portion constructed of coiled wire, U-shaped bolts passing through the legs of the figure and secured to the platform, and a fabric covering for the figure.

In testimony whereof I affix my signature.

ERNEST W. LILJEGRAN.
